DESIGN FOR A SEMI-INDIRECT ELECTRIC LAMP

Bert A. Dickerson, Decatur, Ill., assignor to
Faries Manufacturing Company, Decatur, Ill.

Application February 17, 1937, Serial No. 67,709

Term of patent 3½ years

To all whom it may concern:

Be it known that I, Bert A. Dickerson, a citizen of the United States and a resident of Decatur, in the county of Macon and State of Illinois, have invented a new, original, and ornamental Design for a Semi-Indirect Electric Lamp, of which the following is a specification, reference being had to the accompanying drawing, forming a part thereof.

Fig. 1 is a side elevational view of a semi-indirect electric lamp showing my new design,
Fig. 2 is a top plan view of the base only of
Fig. 1,

Fig. 3 is a front elevational view of Fig. 2.

I claim:

The ornamental design for a semi-indirect electric lamp, substantially as shown.
BERT A. DICKERSON.
